BOTTLE CAP SKIRT CONTRACTING HEAD

William J. Vedder, Syracuse, N. Y., assignor to
Oswego Falls Corporation, Fulton, N. Y., a corporation of New York

Application November 1, 1946, Serial No. 707,098

5 Claims. (Cl. 226—83)

1

This invention relates to contracting heads for contracting the skirt portion of the hood or cover-all bottle caps about the tops of bottles. These caps are formed of sheet material, such as paper, cellophane, or the like, and the marginal, or skirt, portion of the cap is pre-formed, or scored, to form overlapping pleats, or folds, when the skirt portion is contracted about the neck of the bottle. The cap skirt is held in such contracted condition by any suitable means, such as an adhesive. An example of the caps referred to is disclosed in Patent No. 2,268,004, to I. L. Wilcox.

Caps of this type are used very extensively for capping bottles of milk. The caps are applied to the bottles by an automatic machine, such as that shown in Patent No. 2,322,812, to A. A. Barnes, and the cap contracting head herein disclosed is intended particularly for use on that type of machine. It may, however, be mounted upon a suitable standard and operated by hand to cap one bottle at a time.

The invention has as an object a bottle cap skirt contracting head including a cap contracting unit which may be quickly and conveniently detached from the mechanism supporting it, permitting the unit to be conveniently cleaned and sterilized.

The invention has as a further object a cap skirt contracting head embodying a particularly simple structure by which the various parts making up the head, or the cap skirt contracting unit, may be quickly and conveniently dismantled for cleaning, or for repairs.

The invention consists in the novel features and in the combinations and constructions hereinafter set forth and claimed.

In describing this invention, reference is had to the accompanying drawings in which like characters designate corresponding parts in all the views.

Figure 1 is a side elevational view of a cap skirt contracting head embodying my invention, with parts broken away, and parts shown in section, the head being positioned above a bottle with a cap placed on the top thereof.

Figure 2 is a view similar to Figure 1, the bottle having been elevated into the head, and the parts having been moved to cap contracting position.

Figure 3 is a vertical sectional view of the structure shown in Figures 1 and 2, with the cap contracting members removed.

Figure 4 illustrates the cap contracting head mechanism disassembled, with parts shown in section.

2

Figure 5 is a view taken on line 5—5, Figure 1.

Figure 6 is a view, similar to Figure 5, with the actuating cam moved to effect closing of the cap contracting members.

Figure 7 is a view taken on line 7—7, Figure 1.

In general, the invention consists of a support including a bracket and a shaft journaled in the bracket, a cap skirt contracting unit comprising a body detachably secured to the lower end of the shaft and on which there is mounted an annular series of fingers, or cap skirt contracting members, which are movable radially inwardly and outwardly toward and from the center of the cap.

15 The unit further includes means, such as a cam, carried on the shaft and operable to move the skirt contracting members radially inwardly to contract, or fold, the skirt of the cap about the neck of the bottle, this latter operation being effected by rotation, or oscillation, of the shaft in the bracket.

16 The bracket 10 is adapted to be secured to the frame of the cap applying machine. The bracket shown is formed with a laterally extending boss 11 provided with threaded apertures 12, whereby the bracket may be bolted to the machine. The bracket is provided with a bore in which a shaft 14 is journaled. The shaft 14 extends upwardly beyond the top of the bracket, and is provided with an actuating member, shown in the form of a radially extending arm 15 fixedly secured to the shaft by screw 17. The contraction of the cap skirt is brought about by effecting rotation, or partial rotation, of the shaft 14, which is brought about by the outer end of the arm 15 engaging, or being engaged by, a cam or similar part of the cap contracting machine. Preferably, an antifriction roller 18 is mounted upon the outer end of the arm 15.

17 The lower end of the shaft 14 depends below 20 the lower end of the bracket 10 and has secured thereto, by any suitable means, a cam wheel 20 formed with a plurality of teeth or lobes 21. The body 23, of the cap contracting unit, is apertured to receive the lower end of the shaft 14 and is 25 detachably secured thereto by a pin 25 extending through the body and through a transversely extending aperture formed in the lower end of the shaft 14.

26 The body 23 is formed with a plurality of radially extending bosses 27, each of which is formed with a slot 28. A cap skirt contracting member 29 is mounted in each of the slots 28. In the embodiment shown, each of the cap contracting members 29 is pivotally mounted upon a pin 30 30 extending through the boss 27 and projecting at

each end laterally therefrom, whereby the ends of the pins abut, see Figures 5 and 7. All of the pins 30 are held in place by a single means in the form of a screw 32 threaded into the body intermediate one pair of the bosses 27, and being formed with a conical head engaging like ends of the pins 30 positioned in the adjacent bosses whereby, when the screw 32 is tightened, the pins 30 are moved axially in the bosses 27 until the pins are held in abutting relationship, see Figure 7.

The lower ends of the cap contracting members 29 are arranged below the body 23 and are formed with arcuate cap engaging jaws 36. The upper ends of these members extend above the body 23 and are provided with rollers 37 which are engaged by the cam lobes 21. The cap engaging members, or the jaws 36 thereof, are yieldingly urged outwardly by a necklace spring 38 encircling the members above the pivot pins 30.

The bottle B, with a cap C placed on the top thereof, is positioned in axial alinement with the cap contracting unit and, upon relative axial movement between the bottle and the unit, the skirt portion 49 of the cap is engaged by the jaws 36 and folded downwardly about the top of the bottle. This movement positions the jaws 36 immediately below the bead on the bottle top and thereupon the shaft 14 is rotated and the jaws 36 move inwardly by the cam 20, see Figure 2.

The cap contracting members are held in this position for a time sufficient to permit the adhesive to set and thus secure the overlapping folds, or pleats, together, whereupon the shaft 14 is rotated in the opposite direction to permit the spring 38 to release the cap contracting members, whereupon the bottle is lowered, or the cap contracting head raised, to permit the bottle to be discharged from the machine. It will be understood, by those familiar with the bottle capping art, that capping machines include mechanism for effecting such relative axial movement between the bottle and the contracting head.

Cover-all, or hood caps of the type referred to are employed for sanitary protection of the top of the bottle. This, however, is only one of a great many precautions now required by the health department of most all municipalities in protecting milk against contamination. For example, it is also required that all machinery, apparatus, and equipment, used in the processing and packaging of milk, be completely disassembled, cleaned, and sterilized, daily.

In cap applying machines heretofore in use, the cap contracting heads have been assembled in the machines as an integral part thereof and which could not be removed, or disassembled, except by a machine service man having the proper knowledge and tools to do so. Accordingly, the cap contracting heads could not be properly, or effectively, cleaned, although this is highly desirable because anything of a contaminating nature, collecting on the contracting heads, may be transferred to the bottle tops, or caps. Occasionally milk, or milk products, are deposited on the cap contracting head. This happens from various causes, such as a bottle breaking during the capping operation. In such cases, the contracting head should be properly cleaned to prevent the growth of bacteria.

The chief object of this invention resides in a capping head structure, whereby the cap head unit may be quickly and conveniently removed from the capping machine by the regular machine operator and, upon removal, he can conveniently and completely clean the unit and

leave it immersed in a sterilizing solution until he is ready to make the next capping run.

To remove the capping unit, including the body 23, the annular series of fingers 29, and spring 38, it is only necessary for the operator to remove the pin 25. The body 23 is apertured to receive the pin, and the shaft 14 is also provided with a transversely extending aperture 42, whereby the pin is effective to detachably secure the body to the lower end of the shaft in proximity to cam 20. The side walls of the aperture 42 in the shaft diverge outwardly from the axis of the shaft, see Figure 5, whereby relative rotation between the shaft and the body is permitted. The bottom side of the inner portion of the pin 25 is flattened as at 44, see Figures 3 and 4, to provide a greater bearing surface on the bottom wall of the slot 42 in the shaft 14. The outer end of the pin 25 is provided with a spring pressed latch 46 having an end portion 47 being yieldingly positioned in an aperture formed in the top surface of the body 23 by a spring 48, see Figures 4 and 5, the latch 46 serving to prevent accidental displacement of the pin.

Relative rotation between the body 23 and the bracket 10 is prevented by a pin 49 depending from a boss 50 formed on the side of the bracket, the lower end of the pin 49 being positioned in an aperture 51 formed in the body 23. With this arrangement, the shaft 14 may be rotated sufficiently to cause the cam 20 to move the fingers into cap contracting relation, as shown in Figures 2 and 6, and the cap contracting unit is removable from the support by simply removing the pin 25.

Preferably, the device includes a presser pad 54 having an elongated stem 55 slidably mounted in the shaft 14. The presser pad is arranged centrally of the annular series of cap contracting members 29 and is yieldingly urged into engagement with the top of the cap C by a compression spring 57 arranged in the upper portion of the bore in shaft 14, with the upper end of the spring secured to a pin 58 extending transversely of the shaft. The stem 55 is provided with an elongated slot or aperture 59 to receive the pin 25 and limit the downward movement thereof. The pin 25 also serves to detachably secure the presser pad to the shaft 14, the elongated slot permitting the pad and the stem 55 to move upwardly during the cap contracting operation.

It will be observed that at the end of the capping run, it is only necessary to disengage the latch 47 and withdraw the pin 25 to remove the cap contracting unit, including the body 23, the cap contracting members 29, spring 38, and the presser pad 54. These parts may thereupon be easily cleaned and may be kept in a sterile solution until they are remounted on the machine for the next run.

60. What I claim is:

1. A bottle cap skirt contracting head comprising a bracket, a shaft journaled in the bracket, a cap contracting unit including a body detachably mounted on the lower end of said shaft, means cooperable to restrain rotation of said body relative to the bracket, an annular series of cap contracting members mounted upon said body and being movable radially inwardly and outwardly toward and from the center of the cap, means yieldingly urging said members radially outwardly, and cam means carried by said shaft and operable upon rotation thereof to move said cap contracting members radially inwardly to contract the cap skirt against the bottle top.

75 2. A bottle cap skirt contracting head com-

prising a support including a bracket and a shaft journalled in said bracket, a cap skirt contracting unit including a body and an annular series of cap engaging members mounted on the body and movable radially inwardly and outwardly from the center of the cap, a presser pad arranged to engage the top of the cap and having a stem slidably mounted in said shaft, means yieldingly urging said presser pad into engagement with the top of the cap, a single means co-operable to detachably secure said cap contracting unit and said presser pad to the lower end of said shaft, means restraining said cap contracting unit against rotation relative to said shaft, and cam means carried by the shaft and operable upon rotation thereof to move said contracting members into engagement with the skirt portion of the cap to contract the same about the top of the bottle.

3. A bottle cap skirt contracting head comprising a support consisting of a bracket and a shaft journalled in the bracket, a cap skirt contracting unit, an annular series of cap skirt contracting members mounted upon said body and being movable radially inwardly and outwardly toward the center of the cap, a presser pad arranged within said annular series and adapted to engage the top of the cap and having a stem slidably mounted in said shaft, a pin extending through said body, shaft and stem, to detachably secure the body and the presser pad to the lower end of said shaft and to permit relative rotation between said shaft and body, means co-operable to restrain said body from rotation relative to said bracket, means yieldingly urging said cap contracting members outwardly, and cam means carried by said shaft and operable upon rotation thereof to move said cap contracting members radially inwardly to contract the skirt

portion of the cap against the top of the bottle.

4. A bottle cap skirt contracting head comprising a support including a bracket and a shaft journalled in the bracket, a cap skirt contracting unit including a body, an annular series of cap skirt engaging and contracting members pivotally mounted upon the body, each of said members being so mounted upon a pin detachably secured in the body, a single means co-operable to detachably secure all of said pins to the body, means yieldingly urging said contracting members radially outwardly, means operable to detachably secure the cap contracting unit to the support, and cam means carried by the support and operable to move said cap contracting members radially inwardly to contract the cap skirt against the bottle top.
5. A bottle cap skirt contracting head comprising a bracket, a shaft mounted vertically in the bracket and depending therefrom, a cap contracting unit comprising a body and an annular series of cap contracting members mounted on said body and being movable radially inwardly and outwardly toward and from the center of the cap, a single means co-operable to detachably secure said cap contracting unit to said shaft, a cam mounted on the shaft and operable upon rotation thereof to move said cap contracting members radially inwardly to contract the cap skirt against the bottle top.
